UNITED STATES PATENT OFFICE

2,362,754

DEVICE FOR PROJECTING MOVING TIME INDICATIONS

Manfred J. Johnson, New Haven, Conn., assignor to The United States Time Corporation, a corporation of Connecticut

Application January 4, 1944, Serial No. 516,988

7 Claims. (Cl. 58—2)

The present invention relates to improvements in devices for projecting moving time-indications upon screens or the like, i. e., devices having time-indicating means, some of which are in motion at an appropriate speed and which may be projected upon a screen, wall-surface or the like by means of light passing through portions of the device.

One of the objects of the present invention is to provide a superior device of the character referred to, whereby time-indications may be projected in both an accurate and entertaining manner.

Another object of the present invention is to provide a superior device for projecting moving time-indications and which, in addition to projecting such time-indications, will also project portions of the interconnecting gear-members and the like in such manner as to give the entertaining and puzzling impression that one or more members of such gear-train are floating in space.

A further object is to provide a superior device of the character referred to, whereby the indicators may be readily and conveniently adjusted with respect to each other to properly coordinate their respective indications.

With the above and other objects in view, as will appear to those skilled in the art from the present disclosure, this invention includes all features in the said disclosure which are novel over the prior art.

In the accompanying drawings, in which certain modes of carrying out the present invention are shown for illustrative purposes:

Fig. 1 is a face view of one form of device for projecting moving time-indications in accordance with the present invention;

Fig. 2 is an edge view thereof;

Fig. 3 is a broken detail sectional view taken on the line 3—3 of Fig. 1;

Fig. 4 is a similar, but less comprehensive, view taken on either one of the lines 4—4 of Fig. 1; and

Fig. 5 is a showing of the silhouette which would appear upon a screen or the like, when the device shown in the preceding figures is placed intermediate such a screen and an appropriate source of light.

In the particular device illustrated in the accompanying drawings for purposes of making clear one form of the present invention, a substantially-triangular assembly-plate 10 is employed. Rigidly secured to the front face of the lower portion of the said assembly-plate is a base-

plate 11 forming a feature of a synchronous electric motor generally designated by the reference character 12 and having the usual two terminal-leads 13 and 14 which may be connected into 5 any suitable source of alternating current such, for instance, as 110 volt 60-cycle alternating current. The said synchronous motor may be of any suitable form and does not require detailed description herein other than to note that it is provided with a rearwardly-extending drive-shaft 15

propelled, in the instance shown, at 450 R. P. M.

The drive-shaft 15 extends rearwardly through the adjacent portion of the assembly-plate 10 and carries a drive-pinion 16 meshing into and driving a gear-wheel 17 rotatably mounted on the rear face of the assembly-plate 10. The said gear-wheel 17 carries a concentric pinion 18 which in turn, meshes into and drives a gear-wheel 19 carrying a concentric-pinion 20. The pinion 20 just referred to meshes into and drives a gear-wheel 21 which latter, in turn, meshes into and drives a pinion 22.

The pinion 22, last above mentioned, meshes into and drives a transparent relatively-large 25 peripherally-toothed seconds-wheel 23 located adjacent the rear face of the upper portion of the assembly-plate 10 and the rear face of a rectangular transparent dial-plate 24, which latter is rigidly coupled at its lower portion to the front 30 face of the upper portion of the assembly-plate 10, as is indicated in the drawings. The said dial-plate 24 has printed upon or otherwise applied, to its front face a usual annular series of minute and hour designations or indicia 25, as shown in Fig. 1.

In the particular construction shown, the speed of the drive-shaft 15 of the synchronous motor 12 is such that, through the intermediary of the time-train (comprising the parts 16 to 22 inclusive), the said shaft serves to drive the seconds-wheel 23 at a speed of 1 R. P. M.

The seconds-wheel 23 is rigidly mounted upon a bushing-like hub 26 which in turn, is rigidly mounted upon the rear end of a seconds-arbor 27. The said hub 26 is provided with a rearwardly-extending externally-threaded tubular portion 28 of sufficiently-smaller diameter than the main portion of the said hub to provide a rearwardly-facing friction-shoulder 29. Located adjacent the said friction-shoulder 29 is the inner portion of a seconds-pointer 30 extending radially outwardly to a point substantially corresponding to the radius of the minute-divisions of the indicia or markings 25 on the dial-plate 24. In the construction shown, the said sec-

50

55

onds-hand is located very materially to the rear of the dial-plate 24, upon the forward face of which the said indicia or markings 25 are located.

The inner portion of the seconds-pointer 30 above referred to, is rigidly clamped against the adjacent forward face of a tubular hub-member 31 which frictionally bears against the friction-shoulder 29 of the hub 26. Fitting within the hub-member 31 is a helical spring 32 thrusting at its forward end against the adjacent bottom wall of the hollow interior of the said hub-member and thrusting at its rear end against the forward face of an adjusting-nut 33 threadedly connected to the externally-threaded outer end of the tubular portion 28 of the hub 26. As thus constructed and arranged, the spring 32 presses the forward face of the hub-member 31 of the seconds-pointer 30 into frictional engagement with the friction-shoulder 29 of the hub 26 of the seconds-wheel 23. In this manner, the seconds-pointer 30 is frictionally coupled to the seconds-wheel 23 for concurrent movement therewith, but in such manner as to be adjustable with respect thereto in an annular direction.

The forward end of the seconds-arbor 27 is journaled in a transparent front movement-plate 34 located in front of a complementary transparent rear movement-plate 35. The complementary movement-plates 34 and 35 are both located in front of the dial-plate 24 and are held in spaced parallel relationship with respect to each other by means of two (more or less) spacing-washers 36-36 (Fig. 1). The rear movement-plate 35 is spaced forwardly of the dial-plate 24 by two spacing sleeves 37-37, one of which is located in axial alignment with a given one of the afore-said spacing-washers 36-36.

For the purpose of coupling the two movement-plates 34 and 35 together and for coupling both thereof to the dial-plate 24, two screws 38-38 are employed, a given one of which is extended rearwardly through the front movement-plate 34, thence through a spacing-washer 36, through the rear movement-plate 35, thence through the aligned one of the spacing-sleeves 37-37 and into threaded engagement with the dial-plate 24.

Located intermediate the front movement-plate 34 and the rear movement-plate 35 and rigidly coupled to the adjacent portion of the seconds-arbor 27, is a seconds-pinion 39. The said seconds-pinion 39 meshes into and drives a gear-wheel 40 which is rigidly mounted upon a shaft 41 journaled in both of the movement-plates 34 and 35. At a point to the rear of the rear movement-plate 35, the shaft 41 has rigidly mounted thereon a pinion 42 which meshes into and drives a minute-wheel 43. The said minute-wheel 43 is driven through the chain of parts referred to at a speed of 1. R. P. H., and is mounted upon the rear portion of a minute-sleeve 44 rotatably mounted upon a bearing-sleeve 45. The said bearing-sleeve is rigidly mounted at its forward end in the rear movement-plate 35 and extends rearwardly therefrom through the dial-plate 24 so that its interior constitutes a bearing for the seconds-arbor 27, while its exterior provides a bearing for the said minute-sleeve 44.

As before noted, the minute-wheel 43 is mounted upon the rear portion of the minute-sleeve 44, but instead of being rigidly attached thereto the said minute-wheel is frictionally coupled to the said minute-sleeve. The frictional coupling referred to is accomplished by means of a flexible friction-washer 46 interposed between the rear 78

face of the minute-wheel 43 and the forward face of a minute-pinion 47 which is rigidly mounted upon the minute-sleeve 44. At its rear end, the minute-sleeve 44 has rigidly mounted upon it a minute-pointer 48 turning, as usual, at 1 R. P. H.

The minute-pinion 47 before referred to, meshes into and drives a gear-wheel 49 mounted with freedom for rotation upon a stud 50 projecting rearwardly from the rear movement-plate 10 35. The gear-wheel 49 has rigidly secured to its rear face a pinion 51 which meshes into and drives an hour-wheel 52. The said hour-wheel 52 is rigidly mounted upon the forward end of an hour-sleeve 53 which is rotatably mounted upon the adjacent portion of the minute-sleeve 44 15 and extends rearwardly through the dial-plate 24, as indicated in Fig. 3. At a point intermediate the minute-pointer 48 and the dial-plate 24, the hour-sleeve 53 rigidly mounts an hour-pointer 20 54 of any suitable design and turning, as usual, at $\frac{1}{12}$ R. P. H.

For the purpose of resetting the minute-pointer 48 and the hour-pointer 54, a knurled setting-button 55 is located adjacent the front face of 25 the front movement-plate 34, as indicated in Figs. 2 and 3. The said setting-button is rigidly mounted upon the forward end of a setting-shaft 56 extending rearwardly through and bearing in both of the movement-plates 34 and 35. Adjacent its rear end and at a point intermediate the rear movement-plate 35 and the dial-plate 24, the said setting-shaft has rigidly mounted thereon a setting-pinion 57 which meshes into the gear-wheel 49. By turning the setting-button 30 55, the minute-pointer 48 and the hour-pointer 54 may be reset, due to the frictional coupling of the minute-sleeve 44 to its minute-wheel 43, which frictional coupling permits the minute-sleeve 44, the hour-sleeve 53, and associated parts 35 to be turned independently of the drive-mechanism connected to the said minute-wheel 43.

The seconds-pointer 30 may be reset as desired by grasping the knurled rear end of the hub-member 31 of the said seconds-pointer and rotating the same to overcome the frictional coupling between the said hub-member 31 (forming part of the seconds-pointer 30) and the hub 26 of the seconds-wheel 23.

When the device above described is placed intermediate a suitable light-source and a screen, so that the light passes in the direction indicated in Fig. 2, a silhouette of the features of the upper portion of the device will be thrown onto the screen in a manner indicated in Fig. 5. It is preferred to use a suitable opaque mask such as 58, indicated by broken lines in Fig. 2, so that any parts materially beyond the markings or indicia 25 on the dial-plate 24 will be masked-out.

Since the seconds-wheel 23, dial-plate 24 and movement-plates 34 and 35 are transparent, the remaining relatively-non-transparent parts will appear in silhouette on the screen as described.

Preferably, the parts 23, 24, 34 and 35 will be formed of a crystal-clear transparent material 65 such as crystal-clear Lucite, though if desired attractive tints may be given any or all of the said parts. Preferably, the various gears, pinions, and the like will be formed of opaque material such as brass, but here again it is obvious that semi-transparent materials may be used for these parts, since their silhouettes will appear upon the screen if they be but relatively non-transparent as compared to the parts 23, 24, 34 and 35 above referred to.

The device above described when projected on

a screen or the like, will show various of the parts in motion at different rates of speed and in such manner that the gearing, etc., appears to be suspended in space. Thus, not only may accurate time-indications be given to an audience but entertainment may also be afforded such audience insofar as the audience is intrigued by the silhouettes of the moving parts of the mechanism.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. A device for projecting moving time-indications, including in combination: a stationary transparent dial-plate carrying a ring of time-indicia; a transparent wheel mounted adjacent and in substantial parallelism with the said dial-plate and turning substantially-concentrically with respect to the ring of time-indicia thereof; a synchronous electric motor positioned outwardly beyond the ring of time-indicia carried by the said dial-plate and operatively connected to a peripheral portion of the said wheel to turn the same; transparent gear-supporting means also mounted adjacent and in substantial parallelism with the said transparent dial-plate and extending within the ring of time-indicia carried thereby; a first time-indicator driven by the said wheel in position for movement within the boundary of the ring of time-indicia carried by the said transparent dial-plate and relatively-opaque as compared to the said dial-plate, wheel and gear-supporting means; a second time-indicator positioned for movement within the boundary of the ring of time-indicia carried by the said dial-plate and relatively-opaque as compared to the said dial-plate, wheel and gear-supporting means; and a gear-train operatively interconnecting the said first time-indicator and the said second time-indicator and located within the boundary of the ring of time-indicia carried by the said dial-plate, the said gear-train being relatively-opaque as compared to the said gear-supporting means, the said wheel and the said dial-plate.

2. A device for projecting moving time-indications, including in combination: a stationary transparent dial-plate carrying a ring of time-indicia; a transparent seconds-wheel mounted adjacent and in substantial parallelism with the said dial-plate and turning substantially-concentrically with respect to the ring of time-indicia thereof; a synchronous electric motor positioned outwardly beyond the ring of time-indicia carried by the said dial-plate and operatively connected to a peripheral portion of the said seconds-wheel to turn the same at one R. P. M.; transparent gear-supporting means also mounted adjacent and in substantial parallelism with the said transparent dial-plate and extending within the ring of time-indicia carried thereby; a seconds-indicator driven by the second seconds-wheel in position for movement within the boundary of the ring of time-indicia carried by the said transparent dial-plate and relatively-opaque as compared to the said dial-plate, seconds-wheel and gear-supporting means; a time-indicator positioned for movement within the boundary of the ring of time-indicia carried by the said dial-plate and relatively-opaque as compared to the

said dial-plate, seconds-wheel and gear-supporting means; and a gear-train operatively interconnecting the said seconds-indicator and the said time-indicator and located within the boundary of the ring of time-indicia carried by the said dial-plate, the said gear-train being relatively-opaque as compared to the said gear-supporting means, the said seconds-wheel and the said dial-plate.

- 10 3. A device for projecting moving time-indications, including in combination: a stationary transparent dial-plate carrying a ring of time-indicia; a transparent wheel mounted adjacent and in substantial parallelism with the said dial-plate and turning substantially-concentrically with respect to the ring of time-indicia thereof; a synchronous electric motor positioned outwardly beyond the ring of time-indicia carried by the said dial-plate and operatively connected to a peripheral portion of the said wheel to turn the same; transparent gear-supporting means also mounted adjacent and in substantial parallelism with the said transparent dial-plate and extending within the ring of time-indicia carried thereby; a first time-indicator mounted for movement within the boundary of the ring of time-indicia carried by the said transparent dial-plate and relatively-opaque as compared to the said dial-plate, wheel and gear-supporting means; friction-means yieldingly coupling the said first time-indicator to the said transparent wheel with capacity for adjustment with respect thereto; a second time-indicator positioned for movement within the boundary of the ring of time-indicia carried by the said dial-plate and relatively-opaque as compared to the said dial-plate, wheel and gear-supporting means; and a gear-train operatively interconnecting the said first time-indicator and the said second time-indicator and located within the boundary of the ring of time-indicia carried by the said dial-plate, the said gear-train being relatively-opaque as compared to the said gear-supporting means, the said wheel and the said dial-plate.
- 45 4. A device for projecting moving time-indications, including in combination: a stationary transparent dial-plate carrying a ring of time-indicia; a transparent seconds-wheel mounted adjacent and in substantial parallelism with the said dial-plate and turning substantially-concentrically with respect to the ring of time-indicia thereof; a synchronous electric motor positioned outwardly beyond the ring of time-indicia carried by the said dial-plate and operatively connected to a peripheral portion of the said seconds-wheel to turn the same at one R. P. M.; transparent gear-supporting means also mounted adjacent and in substantial parallelism with the said transparent dial-plate and extending within the ring of time-indicia carried thereby; a seconds-indicator mounted in position for movement within the boundary of the ring of time-indicia carried by the said transparent dial-plate and relatively-opaque as compared to the said dial-plate, seconds-wheel and gear-supporting means; friction-means yieldingly connecting the said seconds-indicator to the said transparent seconds-wheel with capacity for adjustment with respect thereto; a time-indicator positioned for movement within the boundary of the ring of time-indicia carried by the said dial-plate and relatively-opaque as compared to the said dial-plate, seconds-wheel and gear-supporting means; and a gear-train operatively interconnecting the said seconds-indicator and the said time-indi-

cator and located within the boundary of the ring of time-indicia carried by the said dial-plate, the said gear-train being relatively-opaque as compared to the said gear-supporting means, the said seconds-wheel and the said dial-plate.

5. A device for projecting moving time-indications, including in combination: a stationary transparent dial-plate carrying a ring of time-indicia; a transparent wheel mounted adjacent and in substantial parallelism with the said dial-plate and turning substantially-concentrically with respect to the ring of time-indicia thereof; a synchronous electric motor positioned outwardly beyond the ring of time-indicia carried by the said dial-plate and operatively connected to a peripheral portion of the said wheel to turn the same; transparent gear-supporting means also mounted adjacent and in substantial parallelism with the said transparent dial-plate and extending within the ring of time-indicia carried thereby; a first time-indicator mounted for movement within the boundary of the ring of time-indicia carried by the said transparent dial-plate and relatively-opaque as compared to the said dial-plate, wheel and gear-supporting means; first friction-means yieldingly coupling the said first time-indicator to the said transparent wheel with capacity for adjustment with respect thereto; a second time-indicator positioned for movement within the boundary of the ring of time-indicia carried by the said dial-plate and relatively-opaque as compared to the said dial-plate, wheel and gear-supporting means; and driving-means yieldingly interconnecting the said first time-indicator and the said second time-indicator and including second friction-means and a gear-train located within the boundary of the ring of time-indicia carried by the said dial-plate, the said gear-train being relatively-opaque as compared to the said gear-supporting means, the said wheel and the said dial-plate.

6. A device for projecting moving time-indications, including in combination: a stationary transparent dial-plate carrying a ring of time-indicia; a transparent seconds-wheel mounted adjacent and in substantial parallelism with the said dial-plate and turning substantially-concentrically with respect to the ring of time-indicia thereof; a synchronous electric motor positioned outwardly beyond the ring of time-indicia carried by the said dial-plate and operatively connected to a peripheral portion of the said seconds-wheel to turn the same at one R. P. M.; transparent gear-supporting means also mounted adjacent and in substantial parallelism with the said transparent dial-plate and extending within the ring of time-indicia carried thereby; a seconds-indicator mounted in position for movement within the boundary of the ring of time-indicia carried by the said transparent dial-plate and relatively-opaque as compared to the said

dial-plate, seconds-wheel and gear-supporting means; first friction-means yieldingly connecting the said seconds-indicator to the said transparent seconds-wheel with capacity for adjustment with respect thereto; a time-indicator positioned for movement within the boundary of the ring of time-indicia carried by the said dial-plate and relatively-opaque as compared to the said dial-plate, seconds-wheel and gear-supporting means; and driving-means yieldingly operatively interconnecting the said seconds-indicator and the said time-indicator and including second friction-means and a gear-train located within the boundary of the ring of time-indicia carried by the said dial-plate, the said gear-train being relatively-opaque as compared to the said gear-supporting means, the said seconds-wheel and the said dial-plate.

7. A device for projecting moving time-indications, including in combination: a stationary transparent dial-plate carrying a ring of time-indicia; a transparent seconds-wheel having gear-teeth upon its periphery and mounted adjacent and in substantial parallelism with the said dial-plate and turning substantially-concentrically with respect to the ring of time-indicia thereof; a synchronous electric motor positioned outwardly beyond the ring of time-indicia carried by the said dial-plate and operatively connected to the gear-teeth on the periphery of the said seconds-wheel to turn the same at one R. P. M.; transparent gear-supporting means also mounted adjacent and in substantial parallelism with the said transparent dial-plate and extending within the ring of the time-indicia carried thereby; a seconds-indicator mounted in position for movement within the boundary of the ring of time-indicia carried by the said transparent dial-plate; first friction-means yieldingly coupling the said seconds-indicator to the said seconds-wheel for turning movement therewith at one R. P. M.; a minute-indicator positioned for movement within the boundary of the ring of time-indicia carried by the said dial-plate; an hour-indicator also positioned for movement within the boundary of the ring of time-indicia carried by the said dial-plate; and driving-means operatively interconnecting the said minute-indicator and the said hour-indicator to the said seconds-wheel for being driven thereby respectively at one R. P. H. and one-twelfth R. P. H., the said driving-means including second yielding friction-means and also including a plurality of gears located within the boundary of the ring of time-indicia carried by the said dial-plate; the said seconds-indicator, the said minute-indicator, the said hour-indicator and the said plurality of gears being relatively-opaque as compared to the said gear-supporting means, the said seconds-wheel and the said dial-plate.

MANFRED J. JOHNSON.
